17-ALKYLSULFONYL AND 17-ALKYLSULFINYL ESTRATRIEN-3-OLS

Raymond M. Dodson, Park Ridge, and Paul B. Sollman, Skokie, Ill., assignors to G. D. Searle & Co., Chicago, Ill., a corporation of Delaware

No Drawing. Application June 23, 1958
Serial No. 743,981

5 Claims. (Cl. 260—397.5)

The present invention relates to a new class of thio-steroids. It is concerned in part with those derivatives of 1,3,5(10)-estratrien-3-ol, its ethers and esters which are substituted at the 17-position by alkylsulfinyl or alkylsulfonyl groups. It is also concerned with 16-dehydro derivatives of these compounds. Accordingly, the compounds of this invention include the estratriene derivatives of the structural formula

and the estratetraene derivatives of the structural formula

in which R can represent hydrogen, (lower)alkyl or acyl and n can represent the integers 1 or 2. The term (lower)alkyl can represent methyl, ethyl, propyl, butyl, amyl, hexyl, heptyl, octyl and branched-chain isomers thereof. Acyl radicals comprehended within the term R are preferably the acyl radicals of hydrocarbon carboxylic acids having fewer than nine carbon atoms. Such acyl radicals can be lower alkanoyl radicals, such as formyl, acetyl, propionyl, butyryl, valeryl, hexanoyl, heptanoyl, octanoyl, and branched-chain isomers thereof. Other suitable acyl radicals are those which are cyclic or partially-cyclic in structure. Representative of such acyl radicals are cyclopentanecarbonyl, cyclohexanecarbonyl, cyclopentaneacetyl, cyclopentanepropionyl, cyclohexaneacetyl, benzoyl, methylbenzoyl, phenylacetyl, and homologs and isomers of the foregoing.

2

The foregoing general structural representation is not to be interpreted as expressing limitations with respect to the configurations of the valence bonds directed from, or the groups bonded to, the sulfur atom. The sulfoxides of this invention include 17-alkylsulfinyl compounds having the partial formula

and

25

in which the opposite configurations of the sulfoxide oxygen are represented by arbitrary means. The invention 30 comprehends compounds in which the side chain attached to position 17 are in the "β" as well as the "α" configurations.

It is further to be noted that for purposes of convenience, the sulfones and sulfoxides are represented 35 herein by their classical covalent bond structures, whereas the modern view, less easily representable, is that these compounds are resonance hybrids of the covalent double bond structure and the semipolar bond structure. It will be obvious that lack of agreement among those skilled 40 in the art as to the precise nature of the valence bonds of sulfones and sulfoxides does not in any way limit the useful applications of the compounds of this invention.

Among the starting materials suitable for the manufacture of the compounds of this invention are the 17-45 alkylthio substitution products of 1,3,5(10)-estratrien-3-ol, their 16-dehydro derivatives and ethers and esters thereof.

The compounds of the invention are prepared by 50 oxidizing a 17-alkylthio-1,3,5(10)-estratrien-3-ol or desired derivative thereof, to the corresponding sulfoxide or sulfone by treatment with a peroxy acid, such as perbenzoic acid. Other peroxide reagents, including performic acid, peracetic acid, and perphthalic acid are suitable for carrying out this oxidation. Treatment of a 55 solution of the desired starting material with approximately one molecular equivalent of perbenzoic acid, for example, yields predominantly a mixture of isomeric sulfoxides, differing in the spacial arrangement of the alkyl radical and oxygen atom with respect to the sulfur. 60 Only small amounts of a sulfone and unreacted starting material are isolated when the oxidation reaction is run in this manner. When a solution of the desired starting material is treated with approximately two molecular 65 equivalents of perbenzoic acid, the principal product is the corresponding sulfone.

Esters of the 3-hydroxyl group can be made by esterification of the product resulting from the oxidation step or alternatively the step of esterification can be carried out prior to the step of oxidation. Esterification is accomplished by treatment with an appropriate acid anhydride or acid chloride and pyridine.

The compounds of this invention have useful pharmacological properties. More specifically, they exhibit an inhibitory effect on the Coxsackie virus. They antagonize the spread of virus infection following administration of cortisone.

This invention will appear more fully from the examples which follow. These examples are set forth by way of illustration only, and it will be understood that the invention is not to be construed as limited in spirit or in scope by the details contained therein, as many modifications in materials and methods will be apparent from this disclosure to those skilled in the art. In these examples quantities are expressed in parts by weight and parts by volume which bear the same relation one to another as kilograms to liters. Temperatures are expressed in degrees centigrade ($^{\circ}$ C.).

Example 1

To a stirred solution of 12.2 parts by weight of 3-hydroxy-1,3,5(10)-estratriene-17 β -thiol and 4.82 parts by weight of sodium methoxide in 300 parts by volume of methanol is added over a period of 5-10 minutes a solution of 6.64 parts by weight of methyl iodide in 50 parts by volume of methanol. The temperature is maintained in the range of about 25-35 $^{\circ}$ during the period of addition and for about 5 minutes thereafter, following which 1300 parts by volume of water and 21 parts by volume of acetic acid are added. The precipitated product is collected on a filter, washed with water and recrystallized from benzene to yield 17 β -methylthio-1,3,5(10)-estratrien-3-ol, melting point 143 $^{\circ}$; specific rotation +61.7 $^{\circ}$ in chloroform solution.

To a solution of 3.02 parts by weight of 17 β -methylthio-1,3,5(10)-estratrien-3-ol in 200 parts by volume of benzene is added a benzene soluton of 1.03 molar equivalents of perbenzoic acid (62 parts by volume of 0.166 molar perbenzoic acid). An insoluble product begins to precipitate after about one half of the perbenzoic acid solution is added. The reaction mixture is allowed to stand for 30 minutes following the addition of the perbenzoic acid solution and then the solid reaction product is recovered by filtration. Recrystallization of the reaction product from a mixture of dimethyl formamide, benzene and Skellysolve B yields 17 β -methylsulfinyl-1,3,5(10)-estratrien-3-ol having the formula

which melts at 287-290 $^{\circ}$ (decomposition).

Example 2

To a solution of 2.75 parts by weight of 17 β -methylthio-1,3,5(10)-estratrien-3-ol in 50 parts by volume of acetic acid is added a solution of 2 molar equivalents of perbenzoic acid in benzene. The reaction mixture is diluted with 200 parts by volume of water, filtered and the solid reaction product thus recovered is dried. After two crystallizations from aqueous acetone and one crystallization from methanol the reaction product; 17 β -methylsul-

55

4
fonyl-1,3,5(10)-estratrien-3-ol melts at 298-300 $^{\circ}$ (decomposition). The product has the formula

65
70

A solution of 0.1 part by weight of 17 β -methylsulfonyl-1,3,5(10)-estratrien-3-ol in 3 parts by volume of pyridine and 3 parts by volume of acetic anhydride is allowed to stand at room temperature for two and one-half hours and then poured into 100 parts by volume of ice water. The oily phase thus precipitated is allowed to stand and is induced to crystallize by stirring. The solid residue is recovered by filtration and crystallized from acetone-water and recrystallized from ethyl acetate to yield 17 β -methylsulfonyl-1,3,5(10)-estratrien-3-ol acetate which melts at 216-218 $^{\circ}$.

Example 3

Two and nine-tenths parts by weight of methyl iodide is added to a solution of 2.7 parts by weight of 3-hydroxy-1,3,5(10)-estratriene-17-thione dissolved in a solution of 1.1 parts by weight of sodium methoxide in 100 parts by volume of methanol. After stirring for 5 minutes, the reaction mixture is diluted with 200 parts by volume of water followed by the addition of 10 parts by volume of acetic acid whereupon a heavy precipitate separates. The insoluble product is collected on a filter and crystallized from mixtures of acetone and petroleum ether to yield 17-methylthio-1,3,5(10),16-estratetraen-3-ol which melts at 142-143 $^{\circ}$ and has a specific rotation of +85.7 $^{\circ}$ in chloroform solution.

To a solution of 5.1 parts by weight of 17-methylthio-1,3,5(10),16-estratetraen-3-ol dissolved in 250 parts by volume of benzene is added a solution of 1.04 molar equivalents of perbenzoic acid in benzene. The reaction mixture is stirred for one and one-half hours following the addition of the perbenzoic acid solution, filtered and the solid reaction product thus obtained crystallized twice from acetone to yield 17-methylsulfinyl-1,3,5(10),16-estratetraen-3-ol which has a melting point of 267-268 $^{\circ}$ and a specific rotation of +27.8 $^{\circ}$ in chloroform. The product has the formula

65
70

A solution of 0.1 part by weight of 17-methylsulfinyl-1,3,5(10),16-estratetraen-3-ol in 3 parts by volume of pyridine and 3 parts by volume of propionic anhydride is allowed to stand at room temperature for 24 hours. The solution is poured into 100 parts by volume of ice water and the oily phase thus precipitated is stirred for one hour. The mixture is extracted with ethyl acetate, the extract washed with water, dried over anhydrous sodium sulfate and concentrated to dryness. The oily residue is dissolved in a mixture of isopropyl ether and hexane and the solution chilled at -70 $^{\circ}$. The supernatant liquid is decanted to leave 17-methylsulfinyl-1,3,5(10),16-estratetraen-3-ol propionate as an oil which exhibits absorp-

5

tion maxima in the infrared spectrum at 5.68, 6.66, 6.81, 7.01, 7.25, 7.36, 8.64, 9.53 and 9.96 microns.

Example 4

A solution of 0.63 part by weight of 17-methylsulfinyl-1,3,5(10),16-estratetraen-3-ol and 50 parts by volume of benzene is treated with 8 parts by volume of a 0.25 molar perbenzoic acid solution in benzene. The reaction mixture is allowed to stand overnight, then diluted with benzene, extracted with water, sodium bicarbonate solution and once again with water. The organic solvent is removed in vacuo and the residue crystallized from benzene-petroleum ether and twice from aqueous ethanol to yield 17-methylsulfonyl-1,3,5(10),16-estratetraen-3-ol having a melting point of 229-231° and a specific rotation of +60° in chloroform. The product has the formula

Example 5

A solution prepared from 9.7 parts of estrone acetate, 8.2 parts of benzyl mercaptan, 37 parts of acetic acid and 1 part of p-toluenesulfonic acid monohydrate is allowed to stand at about 25° for 20 hours. Sodium acetate (3 parts) and ice (100 parts) are added, causing the precipitation of an oily product. The suspension is made slightly basic with sodium carbonate and extracted with several portions of ether. The combined ether extract is washed with water, dried over sodium sulfate and filtered. The residue obtained by concentration of the filtrate is dissolved in benzene and poured on a chromatography column prepared from 190 parts of silica. Elution of the column with benzene and then with a 10 volume percent solution of ethyl acetate in benzene affords first a small amount of benzyl mercaptan. Further elution with a 10 volume percent solution of ethyl acetate in benzene affords an odorless, viscous oil which is the crude dibenzyl-mercaptople of estrone acetate. This compound has the structural formula

A solution of 11.3 parts of the crude dibenzylmercaptone of estrone acetate in 35 parts of ether is slowly added to a solution of 20 parts of sodium in 330 parts of liquid ammonia. The reaction mixture is stirred for 2 hours, after which time an additional 280 parts of ether is added. There is then cautiously added 120 parts of ethanol followed by (after reaction of the sodium is complete) 300 parts of water. The reaction mixture is extracted with ether and this ethereal extract, which contains bibenzyl, is discarded. The aqueous solution or suspension is made acidic by the addition of ammonium chloride and extracted with ether. The residue obtained by concentration of this ethereal extract is crystallized from a mixture of benzene and petroleum ether to afford yellow crystals of 3-hydroxy-1,3,5(10)-estratriene-17-thione. After further purification by recrystallization from benzene, this

6

compound melts at about 212-213°. It gives a pink solution in benzene. This compound has the structural formula

- 15 3-hydroxy-1,3,5(10)-estratriene-17-thione (2.7 parts) is dissolved in a solution of 1.4 parts of sodium ethoxide in 80 parts of ethanol. Ethyl iodide (3.1 parts) is added, and after 5 minutes of reaction time the mixture is diluted with 200 parts of water. Upon the addition of 10 parts of acetic acid, a heavy precipitate separates. This insoluble product is collected on a filter and purified by crystallizations from mixtures of acetone and petroleum ether. This compound is 17-ethylthio-1,3,5(10),16-estratrien-3-ol which has the structural formula

- 35 When a solution of 3 parts of this compound in 160 parts of ethanol is treated over a period of 20 minutes with a total of 20 parts of a 10% sodium hydroxide solution and a total of 5 parts of diethyl sulfate, added alternately and in divided portions, and the reaction mixture is diluted
40 with several times its volume of water, the insoluble product formed is 3-ethoxy-17-ethylthio-1,3,5(10),16-estratriene. For purification, a solution of this product in petroleum ether is washed with several portions of dilute sodium hydroxide solution and with water, following
45 which it is rendered anhydrous and concentrated to a small volume for crystallization.

To a solution of 3.5 parts by weight of 3-ethoxy-17 β -ethylthio-1,3,5(10),16-estratriene in 100 parts by volume of acetic acid is added slowly a solution of 1.03 molar equivalents of perbenzoic acid in about 60 parts by volume of benzene. The reaction mixture is stirred for an additional 30 minutes, diluted with 300 parts by volume of water, 300 parts by volume of ethyl acetate and 300 parts by volume of ether. The mixture is washed with two successive portions of 200 parts by volume of water, then with sodium bicarbonate solution to neutrality and once again with water. The organic solution is dried over sodium sulfate, filtered, concentrated to dryness and the residue crystallized from acetone to yield the 3-ethyl ether of 17 β -ethylsulfinyl-1,3,5(10),16-estratrien-3 α -ol which has the formula

and exhibits absorption maxima in the infrared spectrum at 6.2, 6.65, 6.8 and 9.6 microns.

Example 6

To a solution of 2.7 parts by weight of 3-hydroxy-1,3,5(10)-estratriene-17-thione, 1.1 parts by weight of sodium methoxide and 100 parts by volume of methanol is added 2.9 parts by weight of butyl iodide. The mixture is stirred for 20 minutes, diluted with 200 parts by volume of water and then 10 parts by volume of acetic acid added. The heavy precipitate which is formed is collected on a filter and purified by crystallizations from mixtures of acetone and petroleum ether to give 17-butylthio-1,3,5(10),16-estratetraen-3-ol.

A solution of 3.4 parts by weight of 17-butylthio-1,3,5(10),16-estratetraen-3-ol in 200 parts by volume of methanol is treated over a period of 20 minutes with a total of 20 parts by volume of a 10% sodium hydroxide solution and a total of 5 parts by weight of dimethyl sulfate, added alternately and in divided portions, and the reaction mixture is diluted with several times its volume of water, the insoluble product formed is 3-methoxy-17-butylthio-1,3,5(10),16-estratetraene.

To a solution of 3.6 parts by weight of 3-methoxy-17-butylthio-1,3,5(10),16-estratetraene in 100 parts by volume of acetic acid is added 2.03 molar equivalents of perbenzoic acid dissolved in benzene. The reaction mixture is stirred for an additional 30 minutes and 300 parts by volume of water, 300 parts by volume of ethyl acetate and 300 parts by volume of ether is added. The aqueous layer is separated, washed with 200 parts by volume of 1:1 ethyl acetate-ether and the combined organic solvent portions washed with water, then with sodium bicarbonate solution to neutrality and again with water and dried over anhydrous sodium sulfate. The solvents are removed and the solid residue crystallized from ethanol-water to yield 17-butylsulfonyl - 3 - methoxy-1,3,5(10),16-estratetraene which has the formula

and exhibits absorption maxima in the infrared spectrum at 6.2, 6.65, 6.8, 7.8, 8.7 and 8.9 microns.

Example 7

A solution of sodium hydrosulfide is prepared by passing a stream of hydrogen sulfide gas through a mixture of 110 parts of ethylene glycol monoethyl ether and 7.5 parts of sodium methoxide, until substantially all of the sodium methoxide is consumed, as evidenced by the completion of the exothermic reaction. About 1 hour is a convenient period of time for this reaction.

This solution of sodium hydrosulfide is mixed with 4.2 parts of 17 β -(p-toluenesulfonyloxy)-1,3,5(10)-estratrien-3-ol and heated under reflux for 3 hours. The reaction mixture is then poured into 600 parts of water, acidified with 18 parts of concentrated hydrochloric acid and extracted with several portions of a mixture of ether and benzene. The combined organic extract is washed with water and concentrated to dryness. A solution of the residue in benzene is poured on a chromatography column prepared from 100 parts of silica. An oily product (about 1.6 parts) obtained by elution of the column with a 5 volume percent solution of ethyl acetate in benzene is dissolved in 210 parts of ether, and the ethereal solution is extracted with a total of 1000 parts of 5% sodium hydroxide solution, in several portions. The aqueous, alkaline extract is acidified with dilute hydrochloric acid and extracted with several portions of ether.

This combined ethereal extract is washed with water and concentrated to dryness. The oily residue obtained in this manner is crystallized from a mixture of ether and petroleum ether. Further purification by repeated recrystallization from mixtures of benzene and petroleum ether or by a second chromatographic fractionation on a silica gel column affords purified 3-hydroxy-1,3,5(10)-estratriene-17 α -thiol melting at about 135-136.5° C.

To a stirred solution of 12.2 parts by weight of 3-hydroxy-1,3,5(10)-estratriene-17 α -thiol and 4.82 parts by weight of sodium methoxide in 300 parts by volume of methanol is added over a period of 5-10 minutes a solution of 6.64 parts by weight of methyl iodide in 50 parts by volume of methanol. The temperature is maintained in the range of about 25-35° during the period of addition and for about 5 minutes thereafter, following which 1300 parts by volume of water and 21 parts by volume of acetic acid are added. The precipitated product is collected on a filter, washed with water and recrystallized from benzene to yield 17 α -methylthio-1,3,5(10)-estratrien-3-ol.

To a solution of 3.02 parts by weight of 17 α -methylthio-1,3,5(10)-estratrien-3-ol in 200 parts by volume of benzene is added a benzene solution of 1.03 molar equivalents of perbenzoic acid (62 parts by volume of 0.166 molar perbenzoic acid). An insoluble product begins to precipitate after about one half of the perbenzoic acid solution is added. The reaction mixture is allowed to stand for 30 minutes following the addition of the perbenzoic acid solution and then the solid reaction product is recovered by filtration. Recrystallization of the reaction product from a mixture of dimethyl formamide, benzene and Skellysolve B yields 17 α -methyl-sulfinyl-1,3,5(10)-estratrien-3-ol which has the formula

Example 8

A solution of sodium hydrosulfide is prepared by passing a stream of hydrogen sulfide gas through a mixture of 550 parts of ethylene glycol monoethyl ether and 50 parts of sodium methoxide, until substantially all of the sodium methoxide is consumed, as evidenced by the completion of the exothermic reaction. About 1 hour is a convenient period of time for this reaction.

To this solution is added 20 parts of 3-methoxy-17 β -methanesulfonyloxy-1,3,5(10)-estratriene, and the mixture is heated under reflux for three hours. It is then poured into 2000 parts of water, and the resulting mixture is acidified with 110 parts of concentrated hydrochloric acid, and extracted with a total of 900 parts of ethyl acetate in 3 portions. The ethyl acetate solution is washed successively with water, with sodium bicarbonate solution, and with saturated sodium chloride solution, following which it is rendered anhydrous, filtered, and distilled to dryness. A solution of the residue in the minimum quantity of a 20 volume percent solution of benzene in petroleum ether is poured onto a chromatography column prepared from 400 parts of silica, and the column is eluted with further quantities of the same solvent mixture, followed by mixtures of benzene and petroleum ether containing gradually increasing proportions of benzene. The desired compound, corresponding to a weight peak in the elution curve, is eluted at a satisfactory rate with a 50 volume percent solution of benzene in petroleum ether. Upon crystallizations from aqueous

methanol and from aqueous ethanol these eluate residues afford 3-methoxy-1,3,5(10)-estratriene-17 α -thiol melting at about 77-82° C. and exhibiting a specific rotation of about +31.3° in chloroform solution.

To a stirred solution of 12.2 parts of 3-methoxy-1,3,5(10)-estratriene-17 α -thiol and 4.75 parts of sodium methoxide in 240 parts of methanol is added over a period of 5-10 minutes a solution of 6.5 parts of methyl iodide in 40 parts of methanol. The temperature is maintained in the range of about 25-35° C. during the period of addition and for about 5 minutes thereafter, following which 1300 parts of water and 21 parts of acetic acid are added. The precipitated product is collected on a filter and washed with water. Upon recrystallization from benzene there is obtained 3-methoxy-17 α -methylthio-1,3,5(10)-estratriene.

To a solution of 2.75 parts by weight of 3-methoxy-17 α -methylthio-1,3,5(10)-estratriene in 50 parts by volume of acetic acid is added a solution of 2 molar equivalents of perbenzoic acid in benzene. The reaction mixture is diluted with 200 parts by volume of water, filtered and the solid reaction product thus recovered is dried. Recrystallization from aqueous acetone and then from methanol yields 3-methoxy-17 α -methylsulfonyl-1,3,5(10)-estratriene which has the formula

5

10

What is claimed is:

1. A member of the class consisting of compounds of the structural formula

15 and the compounds of the structural formula

20

25

35

in which R is a member of the group consisting of hydrogen, (lower)alkyl and (lower)alkanoyl and n is a nu-

30 meral selected from the group consisting of 1 and 2.

2. 17 β -methylsulfinyl-1,3,5(10)-estratrien-3-ol.
3. 17 β -methylsulfonyl-1,3,5(10)-estratrien-3-ol.
4. 17-methylsulfinyl-1,3,5(10),16-estratetraen-3-ol.
5. 17-methylsulfonyl-1,3,5(10),16-estratetraen-3-ol.
